CLAIM

The ornamental design for a container lid, as shown and described.

DESCRIPTION

FIG. 1 is a perspective view of the container lid of the invention;

FIG. 2 is a perspective view of the container lid of FIG. 1 showing the invention in alternate position;

FIG. 3 is a side view of the container lid of FIG. 1;

FIG. 4 is a side view of the container lid of FIG. 1;

FIG. 5 is a top plan view of the container lid of FIG. 1;

FIG. 6 is a bottom plan view of the container lid of FIG. 1; and,

FIG. 7 is a sectional view of the container lid of FIG. 1 taken along line 7—7 of FIG. 5.
